Des. 196,407
Patented Sept. 24, 1963

196,407

RADIANT ELECTRIC SPACE HEATER

John J. Fannon, Jr., Grosse Pointe Park, and Charles W. Sawyer, Ann Arbor, Mich., assignors to Hupp Corporation, Cleveland, Ohio, a corporation of Virginia

Filed Dec. 29, 1961, Ser. No. 68,119

Term of patent 7 years

(Cl. D81—10)

Des. 196,407

PAGE 2

FIGURES 1 and 2 are bottom and top perspective views respectively of a radiant electric space heater embodying our new design;

FIGURE 3 is a sectional view taken along lines 3—3 of FIGURE 2;

FIGURES 4 and 5 are like views illustrating a second embodiment thereof;

FIGURE 6 is a sectional view taken along lines 6—6 of FIGURE 5;

FIGURES 7 and 8 are like views illustrating a third embodiment thereof;

FIGURE 9 is a sectional view taken along lines 9—9 of FIGURE 8;

FIGURES 10 and 11 are like views illustrating a fourth embodiment thereof;

FIGURE 12 is a sectional view taken along lines 12—12 of FIGURE 11;

FIGURES 13 and 14 are like views illustrating a fifth embodiment thereof; and

FIGURE 15 is a sectional view taken along lines 15—15 of FIGURE 14.

In all embodiments the ends not shown are substantially a mirror image of the ends shown.

We claim:

The ornamental design for a radiant electric space heater, substantially as shown and described.
